DISPLAY STAND

Glenn B. Jenkins, Charlotte, N.C.
(11301 Idlewild Road, Matthews, N.C. 28105)

Filed Apr. 8, 1971, Ser. No. 132,637

Term of patent 14 years

Int. Cl. D6—04

U.S. Cl. D6—186

FIG. 1

FIG. 4

FIG. 2

FIG. 3

FIG. 1 is a perspective view taken from one side of a display stand embodying my design;

FIG. 2 is an elevational view taken from the side opposite that shown in FIG. 1;

FIG. 3 is a cross-sectional view taken along line 3—3 of FIG. 4; and

FIG. 4 is a top plan view of a modified form of a display stand shown in FIG. 1.

I claim:

The ornamental design for a display stand, as shown and described.
